UNITED STATES PATENT OFFICE.

KARL GAMMEL, OF CLEVELAND, OHIO, ASSIGNOR TO THE CLEVELAND MACARONI COMPANY, OF CLEVELAND, OHIO, A CORPORATION OF OHIO.

APPARATUS FOR DRYING MACARONI AND OTHER EDIBLE PASTES.

1,246,812.

Specification of Letters Patent. Patented Nov. 13, 1917.

Application filed November 27, 1911, Serial No. 662,619. Renewed April 9, 1917. Serial No. 160,887.

To all whom it may concern:

Be it known that I, KARL GAMMEL, a subject of the Emperor of Germany, residing at Cleveland, in the county of Cuyahoga and State of Ohio, have invented certain new and useful Improvements in Apparatus for Drying Macaroni and other Edible Pastes, of which the following is a specification.

10 The primary object of this invention is to provide an apparatus whereby macaroni and similar food products may be dried without bending or splitting the goods and within a shorter space of time than is possible under 15 ordinary, atmospheric conditions. The various other objects of the invention will be more fully set forth in the following description of apparatus embodying the invention, which consists in the new and novel 20 features of construction and combination of parts hereinafter set forth and claimed.

In the accompanying drawing:

Figure 1 is a view in plan of my improved apparatus.

25 Fig. 2 is a central, vertical section of my improved apparatus showing the same adapted for drying macaroni on sticks or supports as it comes from the press.

Fig. 3 represents a sectional view of my 30 improved apparatus adapted for drying edible paste in the form of short cut or similar products.

Fig. 4 is a vertical, sectional view of my 35 improved apparatus showing the same arranged on its side so as to provide drying compartments arranged one above the other.

Referring to the accompanying drawings, the apparatus comprises a preferably rectangular casing 1 provided with a suitable 40 door 2 at one end, and with air inlets 3 arranged in the side thereof preferably in the top. Said inlets are controlled by dampers 4, which may be regulated in any desired manner as by a spring 5 or a weight 6.

45 At one end of the compartment formed in the interior of the casing is arranged a reversible rotary fan or blower 7, which is mounted on a shaft 8 having bearings in brackets 9 supported by the casing. A plurality of heating pipes 10 are arranged adjacent to the fan.

The goods are arranged in the central part of the casing and may be mounted upon the sticks upon which goods, such as 55 macaroni, are subjected to a preliminary

drying. These sticks may be supported upon ledges or projections 11 secured to the casing. If desired, however, the goods may be mounted by means of the sticks upon a carriage or rack 12 adapted to be run into 60 the casing upon a suitable track 14 provided therein. In case the goods comprises edible paste, such as sea shell or short cut, however, these goods are preferably placed in trays which are carried upon suitable 65 racks.

In case the goods are put into the casing and supported therein upon the ledges 11, a partition 13 is preferably provided in the casing, which may be detachably secured in 70 place by means of suitable angle-irons 16, or in any other desired manner, permitting the same to be removed whenever desired. A baffle plate or screen 17 is also preferably arranged between the fan and the goods in 75 such a manner as to better control the circulation of the air on the goods.

At the end of the casing opposite the fan, a valve 18 is pivotally mounted so that the general direction of the air current, as well 80 as its velocity, may be controlled. Said valve is preferably pivoted in line with guide plates 19, which tend to distribute the air currents through the open space at the end of the casing opposite the fan. Said 85 valve is so arranged and proportioned that all of said space may be closed and the air forced to circulate directly through the goods if desired. This arrangement is preferably employed when the goods are mounted 90 on the movable racks, as shown in Figs. 3 to 4 inclusive.

If desired, the casing may be arranged so that two air circulating or drying passages may be arranged one above the other, as 95 shown in Fig. 4. In this case, the upper portion may be used for drying goods on sticks and the lower portion may be used to receive a movable rack, although it is obvious that goods may be placed in only one of 100 the sections if desired.

In operation, the fan is caused to revolve by the pulleys 20 at the desired speed, which causes the air to circulate through and around the goods. In case the partition is 105 used, the valve is arranged in its open position and the air is caused to pass upward through the goods on one side of the partition, thence through the space at the opposite end of the casing, and then downward 110

through the goods on the other side of the partition to the fan. In case the partition is removed, however, and the goods are mounted on movable racks, the valve is placed in its closed position as shown in Fig. 3, thus completely closing the passage at this end of the casing, and causing the air to pass through the goods from one side of the rack to the other. This operation is continued until the drying is completed. During this period, however, both the temperature and the humidity of the air in the casing can be controlled by the heating pipes and by the dampers 22 provided in the air vents. Preferably, also, baffle plates 21 are provided between the fan and the air vents adjacent thereto.

I claim as my invention:

1. An apparatus for drying macaroni and other edible pastes comprising a drying compartment and a fan compartment, a baffle screen between the fan compartment and the drying compartment, a fan in the fan compartment arranged centrally thereof and facing one of the walls of said compartment, a valve controlled air passage at the end of the drying compartment opposite the fan compartment, a valve centrally located in said passage and valve controlled air inlets communicating with said passage.
2. An apparatus for drying macaroni and other edible pastes comprising a drying compartment and a fan compartment, a transverse partition in the fan compartment, a rotary fan in said partition for moving the air in the heating compartment to and from

the drying compartment, a removable partition lengthwise of the drying compartment, a valve controlled air passage between said partition and the wall of the casing, and valve controlled inlets communicating with said passage.

3. An apparatus for drying macaroni and other edible pastes comprising a drying compartment and a fan chamber, a baffle screen between the drying compartment and the fan chamber, a partition in the fan chamber perpendicular to said baffle screen, a rotary fan in said partition arranged to discharge the current of air parallel to the baffle screen, a baffle plate in said fan compartment adapted to intercept a portion of said air and reflect same through the screen into the drying compartment, to produce a circulation of air in the drying compartment.

4. An apparatus for drying macaroni and other edible pastes comprising a casing, a fan arranged at or near one end of said casing for producing a current of air therein, a partition in said casing, a valve arranged adjacent the end of the casing opposite said fan, means for heating the air in said casing, and means for regulating the humidity of the air in said casing, substantially as described.

This specification signed and witnessed this 23rd day of November, A. D. 1911.

KARL GAMMEL.
